(57) **CLAIM**

The ornamental design for an orthotic insert, as shown and described.

DESCRIPTION

FIG. 1 is a upper surface of an orthotic insert showing my new design;

FIG. 2 is a plan view of the underside;

FIG. 3 is a perspective view of the underside;

FIG. 4 is a perspective view of the upper surface;

FIG. 5 is a sectional view taken along line 5—5 of FIG. 1;

FIG. 6 is a side elevational view;

FIG. 7 is a side elevational view opposite the side shown in FIG. 6;

FIG. 8 is an end elevational view of the front end; and,

FIG. 9 is an end elevational view of the rear end.
